(57) **CLAIM**

The ornamental design for a display panel, as shown and
described.

DESCRIPTION

FIG. 1 is a first perspective view of a display panel showing
the new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof;

FIG. 8 is a top view thereof;

FIG. 9 is an enlarged view of an encircled portion of the
display panel in FIG. 2;

FIG. 10 is an enlarged view of an encircled portion of the
display panel in FIG. 5; and,

FIG. 11 is an enlarged view of an encircled portion of the
display panel in FIG. 7.

The broken lines shown in FIGS. 2, 5, 7 and 9–11 depict
encircled portions illustrated in enlargements form no part of
the claimed design. All other broken lines shown in the
drawings depict portions of the display panel that form no
part of the claimed design.
